[57] **CLAIM**

The ornamental design for an outer casing for planetary gear assembly, substantially as shown and described.

DESCRIPTION

FIG. 1 is a perspective front view of an outer casing for planetary gear assembly showing my design;

FIG. 2 is a front elevational view thereof;

FIG. 3 is a rear elevational view thereof;

FIG. 4 is a side view thereof;

FIG. 5 is a view as seen by rotating FIG. 4, 90° to the right;

FIG. 6 is a sectional view taken along the line A—A of FIG. 3.

FIG.1

FIG.3

FIG.5

FIG.2

FIG.4
